DESIGN FOR A COMBINED CIGARETTE HOLDER AND PROTECTOR

Georgia A. Hurley, Findlay, Ohio

Application July 29, 1940, Serial No. 93,994

Term of patent 14 years

To all whom it may concern:

Be it known that I, Georgia A. Hurley, a citizen of the United States, residing in Findlay, in the county of Hancock, State of Ohio, have invented a new, original, and ornamental Design for a Combined Cigarette Holder and Protector, of which the following is a specification, reference being had to the accompanying drawing, forming a part thereof, wherein:

Fig. 1 is a top plan view of a combined cigarette holder and protector showing my new design;

Fig. 2 is a side elevational view; and, Figs. 3 and 4 are views of the front and rear ends respectively of the combined cigarette holder and protector shown in the preceding views.

What I claim is:

The ornamental design for a combined cigarette holder and protector, substantially as shown.

GEORGIA A. HURLEY.
